UNITED STATES PATENT OFFICE.

PETER M. RHODE, OF KENOSHA, WISCONSIN.

APPARATUS FOR APPLYING STRIPS.

1,234,215.

Specification of Letters Patent. Patented July 24, 1917.

Application filed February 15, 1915. Serial No. 8,406.

To all whom it may concern:

Be it known that I, PETER M. RHODE, a citizen of the United States, and a resident of the city of Kenosha, county of Kenosha, 5 and State of Wisconsin, have invented certain new and useful Improvements in Apparatus for Applying Strips, of which the following is a specification.

This invention relates to improvements in 10 apparatus for applying strips of paper and the like and more particularly to an apparatus adapted for applying strips of paper border to bill-boards, though in its broader aspects the invention is not limited to the 15 particular use mentioned.

Among the salient objects of the invention are to provide an apparatus of the character above referred to by means of which a strip, such as the top border of a paneled poster 20 can be quickly and accurately applied to the surface upon which it is being mounted; to provide a construction, which can be attached to a relatively long handle and the strip applied to a portion of the board normally above the reach of the operator while the latter is standing on the ground; to provide an apparatus by means of which the entire operation of attaching the strip from the start to the severing of the same is 25 performed by the one tool; to provide a protective casing which surrounds the roll and from which it is fed when attaching the strip to the board, this casing being preferably of a size to hold a relatively long strip, 30 whereby the operator can apply the panels to a large number of posters without stopping to recharge the casing; to utilize a spring pressed roller carried by the casing for supplying additional pressure to the 35 strip, so as to firmly attach the strip as the apparatus moves forward to feed the roller; to so construct the apparatus that it can be moved free to the right or the left without disarranging the strip, thus permitting the 40 casing to be moved slightly to the right in initially applying the end of the strip; and in general to provide a compact and efficient device, which can be economically manufactured, and is free from complicated parts.

50 In the drawings—

Figure 1 is a top plan view showing the initial operation of the device.

Fig. 2 is a similar view showing the apparatus moved slightly to the right.

55 Fig. 3 is a similar view showing the apparatus as it moves toward the left.

Fig. 4 is a horizontal cross-section through the apparatus, and

Fig. 5 is a side elevation thereof.

Referring to the particular embodiment 60 of my invention shown in the drawings, 1 designates the casing, which is of substantially cylindrical form and of a size sufficient to hold the relatively large roll 2 of paper or the like. The upper end 3 of the 65 casing is removable to permit of the insertion of the roll, and in assembled position this removable end is locked in place by means of a wing nut 4 which has a screw-threaded engagement with a rod 5 extending longitudinally through the central portion of the casing. Surrounding this rod 5 is a tubular member 6 serving as an anti-friction bearing for the roll to insure the 70 paper feeding freely from the casing.

Secured at one side of the casing is a 75 tapered ferrule 7 for detachably receiving an elongated handle 9 so that the operator can attach the paper to portions of the board relatively high off of the ground. As shown 80 in Fig. 5 there is preferably an additional ferrule 8 extending at right angles to the ferrule 7, the purpose of this transverse ferrule being to permit of conveniently applying the strip vertically as well as horizontally, since in bill-board work it is often desirable to form a plain panel border around the entire lithograph.

It is, however, difficult to accurately apply this border, especially the upper strip, with the tools 85 ordinarily employed by crews doing this work, and my invention contemplates an apparatus by which the entire border and particularly the upper strip can be quickly and accurately applied by a single device, 90 95 by one man.

In place of forming the casing 1 of true cylindrical shape I preferably form it with the ends 10 and 11 separated from each other, the end 11 being connected to the 100 cylindrical portion by a relatively flat tangential portion. This flat portion 12 is held parallel to the board when the casing is moved along the latter, and a roller 14 is employed to hold the paper in proper position adjacent the end 11 as it is drawn out from the casing. The roller 14 is carried by the casing, and is resiliently supported by means of coil springs 15 and 16 formed in the sides of the holder 17, which extends 105 through the roller.

A second roller 18 is also supported in a

like manner by means of a wire holder 19 connected to the casing 1, and the sides of this holder contain coil springs 20 and 21 similar to the coil springs of the holder 17. 5 They are, however, so constructed and mounted relative to the casing that in the normal position of the parts the roller is positioned beyond the plane of the flat bearing portion 12 as indicated in Fig. 1. When 10 the apparatus is in full operation the casing 1 is pressed against the board with sufficient force to bring the flat portion 12 in parallel contact with the board. This results in springing the holder 19 away from 15 the casing as shown in Fig. 3, and the roller 18 carried by the holder is thus placed under spring tension by means of the springs 20 and 21. The arrangement last described causes the roller 18 to press the paper 20 against the board with sufficient force to insure its adhering thereto—it being understood that the board has been previously coated with an adhesive substance in the usual manner. 25 From the above description it is obvious that after the free end of the strip is attached to the board, the continued movement of the casing to the left will automatically both feed the paper from the roll and 30 press it firmly onto contact with the adhesively coated board. It is necessary, however, that a sufficient portion of the strip be first adhesively secured to the board in order to pull out the remainder of the strip. 35 Therefore, in starting to apply the strip the operator pulls out the free end until it projects a few inches beyond the roller 18. The casing 1 is then positioned to bring the strip to the desired starting point, and the free 40 end of the strip is then pressed into firm contact with the board. While an ordinary brush or other tool may be employed for holding the free end of the strip initially in contact with the board, I preferably construct an apparatus, so that the necessary initial contact can be made without the employment of an additional tool. 45

As shown in Fig. 1, roller 18 extends beyond the plane of the parallel portion 12, 50 and the necessary adhesion between the end of the strip and the board can be obtained by moving the apparatus to the right and causing the roller 18 to press against the strip.

As shown in Fig. 2 the arrangement of parts 55 is such that upon movement to the right the strip is free to double back on itself. Then upon continued movement in the reverse direction, that is, to the left, the roller is placed under tension, and its carrier extended as shown in Fig. 3.

After the strip has been applied in the manner described, the strip is severed by means of a cutting edge 22 carried adjacent to the roller 18, and, if desired, a portion or 60 all of this cutting edge may be provided

with serrations 23 for facilitating the severing of the strip. The apparatus is thus capable of the entire application of the strip from the start to the finish without the necessity of the operator handling the strip or 70 using any other tool, and the feeding is automatically controlled by the movement of the apparatus along the board. Moreover, since the casing has a capacity to carry a very long roll of paper, the operator can 75 apply the borders to a great many panels without stopping to recharge the apparatus.

For holding the apparatus in upright position, when not in use, the casing is preferably provided with a return bent prong 80 24 which is adapted to engage the top of the board.

In place of using a plain wooden handle I preferably construct the handle 9 as shown in detail in Fig. 5. In this construction the handle comprises two sections 25 and 26 secured together by relatively stiff tubular member 27 formed of rubber or other flexible material. In applying the side panels the handle 9 is 90 inserted in the ferrule 8, and as the casing moves from the top to the bottom, the member 27 allows the handle to assume a gradually increasing angular relation, thus avoiding the necessity of using a shorter handle 95 nearer the bottom of the board. Although in the particular construction shown a flexible tubular member 27 is employed, it is, of course, understood that any other swiveled or flexible connection could be employed. 100

While I have shown and described the invention with reference to the application of paper strips, it is obvious that cloth or other strips could be applied in a similar manner, and the apparatus also employed 105 for attaching strips other than borders. Various other changes in construction and combination of parts can be made without departing from the scope of my invention, as I do not desire to limit the invention except as specified in the appended claims. 110

I claim as my invention:

1. In apparatus for applying strips, the combination with a substantially cylindrical casing adapted to carry and deliver a strip, 115 said casing having a tangentially extending portion, of a roller attached to said casing so as to be placed under tension when brought into alignment with said tangential portion. 120

2. In a portable hand apparatus for applying strips, the combination with a hollow casing having a flat strip applying guiding side, a roller mounted in the casing for supporting a strip roll, a smoothing device 125 movably connected to the casing and normally projecting beyond the strip applying side of the latter and spring tension members acting on the smoothing device. 130

3. In apparatus for applying strips, the

- combination with a casing having a discharge opening, of a smoothing device, a holder for the smoothing device secured to said casing and a cutting edge carried by 5 said holder and positioned beyond said smoothing device.
4. In an apparatus for applying strips, the combination with a casing for holding a roll of the strip, means for automatically 10 attaching the same as it discharges from the casing and a handle for said casing arranged to permit a limited universal movement of the casing relative to the main portion of the handle.
5. In an apparatus for applying strips of paper such as billboards, the combination with a hollow cylindrical casing member having one side substantially flat and forming a strip applying guiding surface and 15 having another side terminating short of the strip applying side to permit the de-
- 20 livery of the strips from the casing, a spring operated smoothing roller normally projecting beyond the strip applying side of the casing and spring tension members co-operating with the smoothing device. 25
6. In an apparatus for applying paper strips to billboards and the like, the combination with a hand supported casing adapted to receive a strip roll, one side of 30 said casing being substantially flat and serving as a strip applying guiding surface, an open throat formed between the strip applying surface and an adjacent part of the casing through which the strip is fed, and a 35 spring tensioned guide roller mounted at the outer side of said throat.

PETER M. RHODE.
